DISPLAY, DIRECTION, OR GUIDE
APPARATUSFrancisco Blasquez and Alejandro Ordorica,
Mexico, D. F., MexicoApplication December 28, 1936, Serial No. 118,008
In Mexico November 30, 1936

5 Claims. (Cl. 40—64)

This invention relates to a display, directing or guide apparatus designed primarily for use at transportation terminals, but it is to be understood that an apparatus, in accordance with this invention, may be employed at any point and used in any connection for which it is found applicable and the invention has for its object to provide, in a manner as hereinafter set forth, an apparatus capable of being affixed to the walls of buildings or to standards and upright supports suitably located at or near street corners, in buildings and at crossings for displaying the names and routes of transportation companies, as well as the location of the terminal stations of such companies, direction of traffic, distances, direction of towns and cities, time tables, intervals of the running of trains, buses and street cars, advertising matter, designs, or any other suitable matter which would be of interest to the public.

Further objects of the invention are to provide, in a manner as hereinafter set forth, an apparatus for the purpose referred to which is simple in its construction and arrangement, strong, durable, compact, pleasing in appearance, thoroughly efficient in its use, readily assembled, including panels carrying matter for display capable of being interchanged and conveniently positioned in and removed from display position and detachably retained in display position, readily assembled to distinctly display matters of interest to the public and comparatively inexpensive to manufacture.

With the foregoing and other objects which may hereinafter appear, the invention consists of the novel construction, combination and arrangement of parts as will be more specifically referred to and are as illustrated in the accompanying drawing, wherein is shown an embodiment of the invention, but it is to be understood that changes, variations and modifications may be resorted to which fall within the scope of the invention as claimed.

In the drawing:

Figure 1 is a front elevation of the apparatus when assembled,

Figure 2 is a section on line 2—2, Figure 1, upon an enlarged scale,

Figure 3 is a section on line 3—3, Figure 1, upon an enlarged scale,

Figure 4 is a section on line 4—4, Figure 3, upon an enlarged scale,

Figure 5 is a section on line 5—5, Figure 1, upon an enlarged scale,

Figure 6 is a section on line 6—6, Figure 2, upon an enlarged scale,

Figure 7 is an elevation of the retaining ele-

ment for the panels looking towards the front face of such element, upon an enlarged scale,

Figures 8 and 9 are front elevations respectively of the head and base panels,

Figure 10 is a section on line 10—10 of Figures 5 and 9, and

Figure 11 is a section on line 11—11, Figure 1,

Figure 12 is a section on line 12—12, Figure 1,

The apparatus includes a panel receiving and holding element 1, a set of intermediate panels 2 of like construction, a head panel 3, a base panel 4, a retaining element 5 for the panels, an upper detachable securing means 6 for one end of element 5 and a lower detachable securing means 7 for the other end of element 5. The panels 2, 3 and 4 have their outer faces provided with suitable matter to be displayed thereby.

The panel receiving or holding element 1 is of rectangular contour and of skeleton or frame-like form. The element 1 includes a top 8, a bottom 9 and a pair of sides 10, 11 which are of greater length than the top 8 and bottom 9.

The top 8, bottom 9 and side 11 are of channel-shape in cross section and open inwardly. The side 10 is formed of a pair of spaced inner face-wise opposed sections 12, 13. The section 12 is flush with the outer faces of the top 8, bottom 9 and side 11. The section 13 is flush with the rear faces of top 8, bottom 9 and side 11. The top 8, bottom 9 and side 11 merge into each other to provide an inwardly opening pocket coextensive with said top, bottom and side 11. The side 10 merges into the top 8 and bottom 9 in a manner to provide an opening 14 to permit of the extension of the panels into the pocket. The latter is formed with an upper stretch by top 8, a lower stretch by bottom 9, and an intermediate stretch by side 11 which merges into the upper and lower stretches. The opening formed by the sections 12, 13 of the side 10 communicates with the upper and lower stretches of the pocket and opposes in parallel spaced relation the intermediate stretch of the pocket.

At the point of emergence of the top 8 with the side 11, the element 1 is formed with an opening 14 and at the point of emergence of the bottom 9 with the side 10, the element 1 is formed with an opening which aligns with the opening 14. The latter is employed for the passage of the upper securing device 6 and the other opening is used for the passage of the securing device 7. The element 1 is formed of any suitable metallic material of the desired gauge.

The panels 2, 3 and 4 are preferably constructed of any suitable metallic material of the 55

gauge.

desired gauge and of suitable cross sectional contour. The panels 2 preferably will be of concavo convex contour in cross section and are so illustrated. Preferably the panels 2 have their cross sectional length less than the cross sectional length of the panels 3, 4.

The number of panels of the intermediate set of panels 2 may be as desired and each panel 2 consists of a body part 15 formed at its top and bottom with inwardly extending right angularly disposed flanges 16, 17. Preferably the panels of the intermediate set of panels are of like size.

The panel 3 consists of a body part 18 formed at its top and bottom with inwardly extending right angularly disposed flanges 19, 20 respectively. The body part 18 at each upper corner thereof is rabbeted as at 21 to provide a clearance.

The panel 4 consists of a body part 22 provided at its top and bottom with inwardly extending right angularly disposed flanges 23, 24. The body part 22 at each lower corner thereof is rabbeted as at 25 to provide a clearance.

The retaining element 5 is formed from a metallic bar 26 of a length substantially equal to the height of element 1. The bar 26 is of a width whereby may be positioned in the opening 13^a formed by the sections 12, 13 of the side 10. The upper and lower ends of the bar 26 are provided respectively with inwardly extending tapered apertured ears 27, 28 for extension into the upper and lower stretches of the pocket. The apertures 29 in the ears 27, 28 are to align with the openings in the element 1 through which extend the upper and lower securing means 6 and 7.

The upper and lower securing means 6, 7 are of like form and each consists of a headed bolt 30 and a clamping nut 31. The heads to bolt 30 are positioned against the outer face of the element 1 and the nuts 31 are positioned against the rear face of element 1.

One of the rabbeted corners of the panel 3 provides a clearance for the shank of the bolt 30 of the securing means 6. One of the lower rabbeted corners of the panel 4 provides a clearance for the shank of the bolt 30 of the securing means 7.

The base panel 4 is positioned within and at the bottom of element 1. The intermediate panels 2 are positioned in the element 1 and are arranged in superimposed relation. The head panel 3 is positioned within element 1 at the upper portion thereof and is superimposed upon the upper one of the intermediate panels. The panel 3 extends into the top 8, and the panel 4 into the bottom 9. The panels 2, 3, and 4 extend into the intermediate stretch of the pocket. The panels 2, 3 and 4 are also arranged in the side 10. The element 5 is positioned within the side 10 and detachably secured to the element 1. The bar 26 of element 5 opposes the sides of the panels which are arranged in the side 10 thereby retaining the panels in the receiver or holder element.

One or more of the panels 2 may be provided with a directing means 32 in the form of an arrow. The panels 2, 3 and 4 have their outer faces provided with any desirable matter which is to be displayed. The apparatus is such that when it is desired to remove a panel 2 and another one substituted therefor, the action may expeditiously be carried out. It is not necessary to completely detach the element 5 when re-

moving and positioning the panels because it can be detached at one end and swung outwardly at its other end to provide sufficient clearance for the removal and substituting of panels.

Removable means, indicated at 33 is provided to prevent the spreading apart of the sections 12, 13 of the side 10. The said means 33 is arranged inwardly of the element 5 when the latter is detachably secured to element.

What we claim is:

1. A display apparatus comprising a panel receiving element of frame-like form including a top, bottom and a pair of sides, said element being formed with an inwardly opening pocket having an upper stretch in said top, a lower stretch in said bottom and an intermediate stretch in one of said sides, said element being formed with an opening in its other side communicating with one end of the upper and lower stretches of said pocket and disposed in parallel spaced relation to the mouth of the intermediate display panels extending through said opening and into said intermediate stretch, a removable head display panel extending through said opening and into said upper and intermediate stretches and seated on said set, a removable base display panel extending through said opening and into said lower and intermediate stretches and supporting said set, a retainer for said panels disposed within and lengthwise of said opening, said retainer being formed with inwardly extending apertured ears at its ends, and means extending through the top and bottom of said element and through said ears for detachably securing the retainer to said element.

2. In a display apparatus, a panel receiving element of frame-like form having a side formed with an opening lengthwise thereof, a head panel for carrying matter to be displayed, a set of intermediate panels for carrying matter to be displayed and a base panel for carrying matter to be displayed, said panels removably mounted in said element in superimposed relation, said opening providing for the insertion of said panels into said element, a retaining element for the panels mounted in said opening, spaced means extending through the receiving and retaining elements for detachably securing them together and the retaining element in panel retaining position, the retaining element being formed with a pair of inwardly extending apertured means for the passage of said spaced means, and each of said panels being formed at its top and bottom with inwardly extending right angularly disposed flanges.

3. In a display apparatus, a panel receiving element of frame-like form having a side formed with an opening lengthwise thereof, a head panel for carrying matter to be displayed, a set of intermediate panels for carrying matter to be displayed and a base panel for carrying matter to be displayed, said panels removably mounted in said element in superimposed relation, said opening providing for the insertion of said panels into said element, a retaining element for the panels mounted in said opening, spaced means extending through the receiving and retaining elements for detachably securing them together and the retaining element in panel retaining position, the retaining element being formed with a pair of inwardly extending apertured means for the passage of said spaced means, and said head and base panels being rabbeted to provide clearances for said spaced means.

4. In a display apparatus, a rectangular re-

- 5 ceiving element of frame-like form for removably holding superposed panels carrying matter to be displayed, said element being formed at one side with an opening for the inserting of the panels 5 therein, a retaining element for the panels mounted lengthwise of said opening, and spaced means extending through said elements for removably securing the retaining element in panel retaining position.
- 10 10 5. In a display apparatus, a rectangular receiving element of frame-like form for removably holding superposed panels carrying matter

to be displayed, said element being formed at one side with an opening for the inserting of the panels therein, a retaining element for the panels mounted lengthwise of said opening, said retaining element being provided at its ends with inwardly extending apertured ears located at the ends of one side of said receiving element, and spaced means extending through said ears and the receiving element for detachably securing the retaining element in panel retaining position. 10
